CLAIM

The ornamental design for a cooling vest for gel-pack inserts, as shown and described.

DESCRIPTION

FIG. 1 is a front elevation view of a cooling vest for gel-pack inserts showing my new design, the rear side being a mirror image thereof;

FIG. 2 is a right elevation view thereof, the opposite side being a mirror image thereof;

FIG. 3 is a top plan view thereof;

FIG. 4 is a bottom plan view thereof; and,

FIG. 5 is an isometric view thereof.

The dashed lines in all of the foregoing figures represent stitching.
